ELECTRICAL PRECIPITATOR

James Hugh Hamilton, Salt Lake City, Utah, assignor to Western Precipitation Corporation, Los Angeles, Calif., a corporation of California

Application February 1, 1946, Serial No. 644,809

9 Claims. (Cl. 183—7)

1

This invention relates to electrical precipitators and more particularly to rapping devices for removing accumulated material from electrodes of electrical precipitators by subjecting the electrodes to mechanical shock.

An object of the invention is to provide an improved electrode rapping device utilizing a fluid pressure reaction jet for supplying the required energy. Another object is to provide in such a device means whereby danger of short-circuiting or grounding of the electrodes may be eliminated.

A further object is to provide a relatively simple and sturdy electrode rapper which may be automatically controlled and which requires a minimum of attention and maintenance.

Typically, the electrode rapping mechanism of the invention includes a striker member positioned in spaced relation to a member of an electrode structure, a fluid pressure reaction jet orifice mounted in driving relation on one of the members, and means for intermittently supplying fluid pressure to the reaction jet to urge the one member into engagement with the other member.

The invention will be described hereinafter with greater particularity, reference being had to the accompanying drawings wherein:

Fig. 1 is a longitudinal sectional view of an electrical precipitator embodying the invention, taken along the plane of the line 1—1 of Fig. 2; 30

Fig. 2 is a transverse sectional view taken along the plane of the line 2—2 of Fig. 1;

Fig. 3 is a fragmentary elevation of the left-hand end of the high tension electrode structure as seen in Fig. 1, parts being broken away to show interior construction;

Figs. 4 and 5 are detail views of the left- and right-hand ends, respectively, of the rapper bar looking in the direction of the arrows 4—4 and 5—5 of Fig. 1;

Fig. 6 is a plan view of parts of a modified form of the apparatus, and

Fig. 7 is an elevational view of the parts shown in Fig. 6.

Referring to Figs. 1 through 5 of the drawings, there is shown an electrical precipitator having a housing 10, gas inlet and gas outlet ducts 11 and 12, and a hopper 13 at the bottom of the housing for collecting precipitated material. Gas to be cleaned flows through the housing in the directional sense indicated by the arrow in Fig. 1, passing between spaced, alternately arranged, longitudinally disposed curtains of high tension or discharge electrodes 14 and low tension or collecting electrodes 15, between which a high

2

potential electrical field is maintained by means well-known in the art. In the zones between such complementary electrode curtains, ionization and precipitation of gas-borne particles 5 occurs in well-known manner.

Much of the precipitated matter adheres to the electrodes and must be periodically removed if the apparatus is to function efficiently. As specifically disclosed herein, the electrode rapping 10 mechanism is constructed and arranged for rapping high tension electrodes, but as will be readily apparent, it may be adapted, in the light of the disclosure, to rap low tension electrodes or other similar structures.

15 Referring to Figs. 1 and 2, it will be seen that the high tension electrode structure and rapping mechanism are completely insulated from the housing 10, being mounted on insulators 16 and 17. As will more fully appear hereinafter, a 20 rubber or other insulating hose 18 prevents grounding of the high tension electrode structure. Insulators 16 carry, in suitable bearings, a lateral pipe 19, from the ends of which depend nipples 20. A second length of lateral pipe 21, 25 provided with capped ends, is connected to the nipples 20 by T's. Pipe 21 has the dual function of supporting the left ends of the high tension electrode supporting bars 22 and providing a header for distributing fluid under pressure to the flexible lines 23. The fluid preferably is compressed air or other gas and is obtained from a source, such as the tank 24, and led to the header 21 through suitable conduits including hose 18, pipe 19 and nipples 20.

30 Lines 23 may be made from lengths of pipe formed with a coiled turn 25 to provide flexibility or resiliency at the lower ends of the lines in the direction of gas flow, together with relative lateral rigidity. The lower ends of the lines are fitted with nozzles or reaction jets 26. Rapper bars 27 are supported at their left ends by the lines 23.

The high tension electrode supporting structure located near the outlet end of the precipitator is similar to that just described, but it does not provide a pressure fluid system nor any reaction jets; its sole function is to carry the right end of the high tension electrode structure.

35 As best seen in Fig. 5, a slot 28 is formed near the right end of rapper bar 27 through which extends a rigid vertical guide 29, the rapper bar being mounted in a sling 30 for limited longitudinal movement with reference to the guide.

The discharge electrode elements 14 may take 55 the form of twisted square metal rods provided

with hooks at their tops, as best seen in Fig. 3. These elements are inserted in suitable holes in the electrode supporting bars 22 and depend through longitudinal slots 31 provided in the rapper bars 27.

In operation, a rapper bar 27 is intermittently driven longitudinally against the electrode elements received in its slots 31 by intermittent reaction of its jet 26. Slots 31 are elongated longitudinally of rapper bars 27, that is, they are elongated in the direction of movement of the bar. In the normal or rest position illustrated in Figs. 3, 4 and 5, the left end face of each slot 31 is spaced from the electrode element 14 received in the slot. Under the force of the reaction to fluid issuing from jet 26, bar 27 first moves freely a limited distance transversely of the electrode elements and thus gains momentum before the normally spaced end face of each slot 31 strikes the electrode member therein. The bar 27 thus acts as a striker bar which because of the elongated character of apertures 31 is driven sharply against the electrode elements by its movement transversely thereof. Such action jars the electrode elements and effectively dislodges deposited dust or other matter which falls into the hopper 13. The intermittent action is controlled by a solenoid valve 32 positioned in the line from the source of pressure fluid, the valve being actuated at preselected intervals to pass to the jets increments of fluid under pressure. Action of the valve may be timed by an automatic timing switch (not shown).

Preferably, the valve 32 provides a series of impulses at intervals of a few seconds. On each impulse, the valve is open for only a fraction of a second, so that the reaction force of the jet is stopped before the rapper bar reaches the end of its stroke, the momentum of the bar being sufficient to bring it into shock contact with the electrode elements. A further rapping contact with the electrode elements occurs when the rapper bar returns toward its rest position. The interval between successive impulses should be sufficient to allow the swinging movement of the rapper bar to subside, an interval of about three to five seconds usually being sufficient for this purpose.

The rest position of the rapper bar may be determined by gravity, by the position of the right end of the slot 28 in which the guide is received, by a combination of the two, or by other appropriate means. The coiled supporting line 23 provides a resilient mounting for the rapper bar that biases the bar toward a normal rest position as determined by engagement of the right end of the slot 28 with the rapper bar, in which the left-hand end faces of slots 31 are spaced from electrodes 14.

It will be understood that a suitable source of high potential is connected to the complementary electrode curtains 14 and 15 in the usual way. As shown, the collecting electrodes 15 are grounded to the housing and the high tension electrode structure is insulated therefrom.

In the specific apparatus illustrated, the collecting electrodes may be cleaned in any desired way, as by manual rapping, flushing with liquid or the like.

The modified embodiment of the invention shown in Figs. 6 and 7 differs from that hereinbefore described in that the electrode elements 14 do not ride in slots in the lower- or tie-bar 27' but are secured firmly to the latter, whereby the free ends of the electrode elements may be flexed in unison. The lower bar 27' is, in effect, an in-

tegral part of the high tension electrode curtain. It is intermittently driven by the reaction jet 26' into jarring engagement with a fixed insulated anvil or striker 33, the shock of its impact against the striker member 33 being transmitted to the electrode elements 14 to dislodge adhering matter. A stop 34, also insulated from the housing, acts as a striker on the return movement of the lower bar 27'.

From the foregoing description, it will be seen that there has been provided an electrode rapping mechanism utilizing fluid pressure jet reaction to obtain simple and effective rapping of material collecting members, and that various modifications may be made in the form and arrangement of the elements without departing from the principles of the invention as defined in the claims.

I claim:

1. In an electrical precipitator including complementary electrodes one of which comprises a curtain of spaced electrode elements, an electrode rapping mechanism which comprises a rapping bar providing a plurality of spaced elongated apertures loosely receiving said electrode elements, fluid reaction jet means mounted in driving relation on said rapping bar, and means for intermittently supplying fluid pressure to said reaction jet means to drive said rapping bar sharply against said electrode elements.

2. In an electrical precipitator including complementary electrodes one of which comprises a curtain of spaced, parallel suspended electrode elements, an electrode rapping mechanism which comprises a rapping bar providing a plurality of spaced elongated apertures loosely receiving the lower ends of said electrode elements, means mounting said rapping bar for limited oscillatory movement, fluid pressure reaction jet means mounted in driving relation on said rapping bar, and means for intermittently supplying fluid pressure to said reaction jet means to drive said rapping bar sharply against said electrode elements.

3. In an electrical precipitator, a high tension electrode structure and rapping mechanism which comprises an upper longitudinal electrode supporting bar, insulating means mounting said supporting bar in the precipitator, a plurality of spaced electrode elements suspended from said bar, a longitudinal electrode rapping bar providing a plurality of spaced elongated apertures loosely receiving the lower ends of said electrode elements, said rapping bar being substantially parallel to said supporting bar, means suspending said rapping bar from said insulating means for limited oscillatory movement substantially parallel to said supporting bar, fluid pressure reaction jet means mounted in driving relation on said rapping bar, and means for intermittently supplying fluid pressure to said reaction jet means to drive said rapping bar sharply against said electrode elements.

4. In an electrical precipitator, a high tension electrode structure and rapping mechanism which comprises insulating means supporting a plurality of spaced, parallel high tension electrode elements in the precipitator, one end of each element being fixed in said supporting means, the other end of each element being free to flex, a tie-bar joining said other ends of said electrode elements whereby said other ends may be flexed in unison, a relatively fixed striker member positioned in normally spaced relation to said tie-bar, fluid pressure reaction jet means

mounted in driving relation on said tie-bar, and means for intermittently supplying fluid pressure to said reaction jet means to drive said tie-bar sharply against said striker member.

5. In an electrical precipitator having an electrode structure which comprises a curtain of spaced parallel electrode elements, an electrode rapping mechanism which comprises: a rapping bar mounted for limited movement transversely of the electrode elements and provided with a plurality of apertures elongated in the direction of said movement for receiving the electrode elements; a fluid reaction jet mounted on the rapping bar; and means for supplying fluid under pressure to said jet, whereby the rapping bar is moved by the reaction to the fluid issuing from the jet to strike all the electrode elements.

6. In an electrical precipitator having an electrode structure which comprises a curtain with spaced parallel electrode elements, an electrode rapping mechanism which comprises: a rapping bar provided with a plurality of apertures elongated longitudinally of the bar; resilient suspension means for the rapping bar supporting the bar for limited longitudinal movement and biasing the bar toward a normal position in which the faces at one end of the apertures are normally spaced from the electrode elements; a fluid reaction jet mounted on the rapping bar; and means for supplying fluid under pressure to said jet, whereby the rapping bar is moved by the reaction to the fluid issuing from the jet to strike all the electrode elements.

7. An electrode rapping mechanism comprising a striker member having a face normally positioned in spaced relation to a member of an electrode structure, one of said members being movable into contact with the other of said members, jet forming nozzle means mounted on said one member in a position to move said one member by force derived from the reaction to the jet,

and means for intermittently supplying fluid under pressure to said jet forming nozzle means to drive said one member sharply against the other of said members.

5 8. An electrode rapping mechanism comprising a striker member having a face normally positioned in spaced relation to a member of an electrode structure, said striker member being movable into contact with the electrode member, jet forming nozzle means mounted on the striker member in a position to move said member by force derived from the reaction to the jet, and means for intermittently supplying fluid under pressure to said jet forming nozzle means to drive said striker member sharply against the electrode member.

20 9. An electrode rapping mechanism comprising a striker member having a face normally positioned in spaced relation to a member of an electrode structure, said electrode member being movable into contact with the striker member, jet forming nozzle means mounted on the electrode member in a position to move said member by force derived from the reaction to the jet, and means for intermittently supplying fluid under pressure to said jet forming nozzle means to drive said electrode member sharply against the striker member.
